BEVERAGE CONTAINER

Bernard H. Cooper, Cleveland, Ohio

Application February 24, 1936, Serial No. 65,238

3 Claims. (Cl. 65—13)

This invention relates to a beverage container.

An object of the invention is to provide an improved beverage container from which the beverage may be drunk.

5 Another object is to provide an improved beverage container which will be attractive and unusual in appearance.

Another object is to provide a beverage container which may serve as a source of amusement.

10 Another object is to provide an improved beverage container which will limit the rate at which the beverage may be drunk.

Other objects will hereinafter appear.

15 The invention will better be understood from the description of three practical embodiments thereof, illustrated in the accompanying drawing, in which:

Figure 1 is a side elevation view, partly broken away and shown in section, of one embodiment of the invention showing a person drinking therefrom;

Figure 2 is a similar side elevation of another embodiment of the invention; and

20 Figure 3 is a view similar to Figures 1 and 2, showing a third embodiment of the invention.

As illustrated in Figure 1, the container consists of an integral hollow shell comprising a flat bottom 1, an annular wall 2 upon which is formed a handle 3, the upper end of the annular wall being flared and given the configuration of a part of a human head having a chin 4, nose 5, upper and lower lips 6 and 7 respectively, forehead 8, a part of the head 9, and providing between the forehead and wall 9 an opening 10 through which the container may be filled or washed.

The opening or orifice through which the liquid may be drunk constitutes the mouth of the face formed on the receptacle, being between the lips 6 and 7.

In order to drink from the container without spilling the beverage, it is necessary for the user to impress his lips upon the lips of the face of the article, as shown in the first figure of the drawing, and to tilt the container upwardly in the ordinary manner.

The nose and forehead 5 and 8 prevent the liquid from running over at the filling opening 10 and are adapted to abut the face of the user to limit the upward inclination of the container, so that no liquid will pass over the wall 8 thereof.

In Figure 2, a very similar type of container 55 is shown having a bottom 101, annular wall 102,

handle 103, and a face consisting of chin 104, nose 105, lips 106, and 107, and forehead 108.

In this form, however, beneath the upper lip 106 is formed a tongue 111, which, with the lower lip 107, forms an elongated curved passage restricting the flow of liquid and rendering the drinking from the device somewhat slower.

Also a flange 112 is formed about the filling opening of the article and a lid or cover, in the form of a hat consisting of a crown 113 and a 10 brim 114, is provided to fit on this flange and to close the container.

While the container as illustrated may be made of ceramic material, glass, or the like, the hat may most conveniently be made of sheet metal, 15 and may be permanently attached to the container by a hinge, or may be interchangeable with other hat-like covers of different configurations which may be transferred from one container to another. Thus different effects may 20 be imparted to the face of the container by combination with different styles of hats.

Figure 3 shows an embodiment in which the drinking orifice is incorporated in a separate piece from the lower part of the container, which 25 piece also serves the function of the cover of Figure 2. In this embodiment, the container consists of a flat base 201 having formed integrally therewith a wall 202 and a handle 203.

The upper end of wall 202 terminates in a 30 cylindrical flange 215, providing a shoulder 216 upon which the top or cover portion of the article may fit.

This is shown as comprising a dome-shaped head portion 217 between which and the shoulder 35 may be positioned a gasket 218, the dome including upper and lower lips 206 and 207, respectively, defining a drinking orifice, and including other features such as nose 205 and forehead 208. The head or cover portion is clamped upon 40 the lower portion of the container by means of wire loop 219, pivotally connected to a wire loop-shaped handle 220, having its ends engaged with centrally recessed bosses 221 formed on wall 222, the loop and handle providing a toggle-like 45 action as is well known in fruit jars and the like.

While I have described the illustrated embodiments of my invention in some particularity, obviously many variations and modifications thereof will readily occur to those skilled in 50 the art to which they appertain, and I do not therefore limit myself to the precise details shown and described, but claim as my invention all embodiments, variations, and modifications coming within the scope of the subjoined claims. 55

I claim:

1. An article of manufacture comprising a hollow container having a continuous peripheral wall provided with an upward extension at one side thereof, the extension having a drinking orifice formed therethrough, a relatively broad substantially flat surface formed on the extension about the orifice and adapted to be engaged by the lips of a user, said surface constituting part of a representation of a face formed on the exterior of said extension, the orifice being the mouth thereof, and a portion of the wall representing a tongue associated with said mouth and positioned to restrict flow of liquid through the orifice to a relatively narrow curved path.
2. An article of manufacture comprising a hollow container having a continuous peripheral wall provided with an upward extension at one side thereof, the extension having a drinking orifice formed therethrough, a relatively broad substantially flat surface formed on the extension about the orifice and adapted to be engaged

by the lips of the user, and constituting part of a representation formed on the exterior of said extension, the breadth of the surface being sufficient to preclude any part of the device entering the mouth of the user while drinking therefrom. 5

3. An article of manufacture comprising a hollow container having a continuous peripheral wall provided with an upward extension at one side thereof, the extension having a drinking 10 orifice formed therethrough, a relatively broad substantially flat surface formed on the extension about the orifice and adapted to be engaged by the lips of the user, and constituting part of a representation formed on the exterior of said 15 extension, the breadth of the surface being sufficient to preclude any part of the device entering the mouth of the user while drinking therefrom, the material about the orifice restricting the liquid passing therethrough to a relatively 20 narrow curved path.
